UNITED STATES PATENT OFFICE.

JAMES A. DORAN, OF PROVIDENCE, RHODE ISLAND.

COLLAR-SUPPORTER.

No. 911,216.

Specification of Letters Patent.

Patented Feb. 2, 1909.

Application filed November 7, 1908. Serial No. 461,506.

To all whom it may concern:

Be it known that I, JAMES A. DORAN, a citizen of the United States, residing at Providence, in the county of Providence and State of Rhode Island, have invented a certain new and useful Improvement in Collar-Supporters, of which the following is a full, clear, and exact description.

This invention relates primarily to supporters for retaining in position lace and other soft and flexible collars commonly worn in connection with ladies' dresses.

The object of the invention is to provide a collar supporter of this character of simple and economical construction, and one in which the bar and its attaching means are constructed as a unit and inseparable, and thus the possibility of losing any of the parts of the device avoided.

The invention consists in a collar supporter, comprising a bar having at its opposite ends a pivoted spring pin or prong, constructed and arranged to be readily inserted in the material of the collar, all as I will proceed now more particularly to set forth and finally claim.

In the accompanying drawings, illustrating the invention, in the several figures of which like parts are similarly designated, Figure 1 is an edge view of one form of the device embodying the invention. Fig. 2 is a plan view of the same. Figs. 3 and 4 are, respectively, plan and edge views, on a larger scale, of the front plate for securing the pin in place. Figs. 5 and 6 are, respectively, plan and edge views, on a larger scale, of the spring plate for coacting with the pin. Fig. 7 is a cross-section, on a larger scale, taken substantially in the plane of line A B, Fig. 2, the pin being broken away. Fig. 8 is a detail view, in partial section and elevation, showing the pin and its attaching parts assembled before applying to the bar. Fig. 9 is a plan view of a modified form of the invention. Fig. 10 is a plan view of the blank for forming the bar of the construction shown in Fig. 9. Fig. 11 is a plan view of the blank of Fig. 9 with its edges rolled over. Fig. 12 is a cross-section, on a larger scale, taken substantially in the plane of line C—D, Fig. 9, and looking in the direction of the arrow, the pin being broken away. Figs. 13 and 14 are edge views of a portion of the supporter, showing modified forms of pins.

The bar 1, Figs. 1 and 2, may be of pearl, horn, celluloid, or any other suitable light

and sufficiently stiff material, and is preferably constructed with the enlarged portions 2 at its ends, which are recessed, as at 3, Fig. 7, the bottoms of said recesses being slightly 60 deeper at their centers than at the edges, as shown at 4. The portions 2 are also recessed upon their opposite sides, as at 5, coinciding with the recesses 3. Openings 6, 6, are made through the bar upon diametrically opposite sides of the recesses, and extend from the bottom of the recess 3 to the bottom of the recess 5.

Within the recesses 3, are pivoted spring pins or prongs adapted to be engaged in the 70 material of the collar to retain the collar in proper upright position. The pin may be constructed of a bent, and if desired shouldered, portion 7, and an elongated head 8, preferably of rectangular shape in cross-section, and it is secured in a front plate 9 (see Figs. 3 and 4) by passing its portion 7 through an elongated opening 10 in said plate, the head 8 of the pin engaging depressions 11, 11, formed upon opposite sides of 80 the opening 10 in said plate. As shown in Figs. 3 and 4, the plate 9 is provided with diametrically opposite ears 12, 12, and diametrically opposite lugs 13, 13.

A spring plate 14 (Figs. 5 and 6) having a 85 central depression 15, and oppositely arranged notches or cut-away portions 16, 16, and 17, 17, is adapted to be placed upon the underside of the front plate 9, with the ears 12, 12, and lugs 13, 13, of plates 9 registering 90 respectively with the notches 16, 16 and 17, 17 of the spring plate 14, and the ears 12 bent down within the notches 16, and under the plate 14, thus locking the front plate 9 and spring plate 14 together, with the head 8 of 95 pin 7 in engagement with the depressions 11 and 15 in the said plates. The pin as thus secured between the plates is placed in the recess 3 in the bar 1 with the lugs 13 passed through the openings 6 and bent up against 100 the bottom of the recess 5 to thus securely fasten the pin and its attached plates to the bar. Any suitable covering or filling may be placed in the recess 5 to cover and conceal the ends of the lugs 13 and to provide a finish 105 for the surface of the bar. As shown in Fig. 7, this filling is formed of a piece of metal 18 or other suitable flexible material of the approximate shape of the recess 5 adapted to be forced into the undercut edges 19 of the 110 recess. When thus assembled, the cap plate 9 and its attached spring plate 14 rests upon

the bottom of the recess 3 with the depressed central portion 15 of the spring plate above the surface of the deeper portion of the recess to thereby obtain the desired spring action of 5 the plate when the pin is moved to its open and closed positions.

As shown in Figs. 9, 10, 11 and 12, the bar 20 may be constructed of sheet metal, and 10 preferably formed from a blank, such as shown in Fig. 10, having the enlarged ends 21, the edges of which may be turned up at right angles, as at 22, Fig. 12, to form cups or recesses to receive the pin and its front plate 23 and the spring plate 24. In this form of 15 the device, the front plate is formed without ears or lugs, as in the construction above described, and the pin and plates are assembled as before described, and placed in the cups or recesses, and the edges of the cups or 20 recesses turned or rolled inward over the front plate, as clearly shown at 25 in Fig. 12, to secure the parts in place. In this form of the device, also, the central portion of the 25 spring plate 24 is raised sufficiently above the surface of the bar to obtain the desired spring action of the plate when the pin is moved to its open and closed positions. The edges of the bar between the enlarged and 30 recessed or recessed ends may be rolled or curled, as shown at 26, Figs. 9 and 11, to stiffen the bar.

As shown in Figs. 1, 2 and 9, the pins are pivoted upon the face of the bar with their points extending longitudinally in opposite 35 directions with relation to the face of the bar and coacting with the face of the bar to retain the pins in locking engagement with the material of the collar.

As shown in Figs. 13 and 14, the pin is bent 40 to form a shoulder, and in Fig. 13, this shoulder, 27, is arranged a little less than a right angle to the plane of the bar, when the pin is in closed position, while in Fig. 14, the shoulder, 28, is arranged substantially at right angles 45 to the plane of the bar. As shown in Fig. 14, the pin is inserted in the material so that the material will engage the shouldered portion thereof.

By the construction described, the pins 50 are maintained in their closed position by the action of the spring plates, and furthermore, by the bent (Figs. 1 and 8) or bent and shouldered (Figs. 13 and 14) forms of the pins, the longitudinal strain or pull of the 55 material upon the pins will aid in holding the pins in closed position.

In applying the supporter to a collar, the pins are turned to the open position and maintained in such position by their spring 60 plates and the pin at one end inserted in the material of the collar at the proper place and then closed, in which position it is securely held by its spring plate. The collar is then stretched to proper shape and placed over 65 the pin at the other end of the supporter,

and that pin closed and securely held in such closed position by its spring plate. Thus, it will be seen that, the supporter may be easily and quickly applied and will be securely fastened to the collar against accidental displacement by coming in contact with the wearer's neck. 70

In order to remove the supporter, it is only necessary to raise the pin points from the surface of the bar or to an open position, 75 as shown at the lower end of Fig. 1, when the material of the collar may be disengaged readily from the pins, the pins being maintained in said open position by the action of their spring plates. 80

The bar and its attached fastening pins constructed and combined as above described constitute a unitary collar supporter, without separate or detachable fastening means, and therefore, the possibility of losing or misplacing any of the parts of the device is avoided. 85

It is to be noted, that the pins are pivoted to the bar so as to be movable toward and from the face of the bar, as distinguished 90 from being movable parallel with the face of the bar, and to describe this difference, I have specified the movement as being outwardly from the face of the bar.

I have herein described my invention in 95 connection with its use as a collar supporter, but I wish to be understood as not limiting the invention to this particular use, since the device is applicable for use in connection with other articles of wearing apparel, or other 100 articles of thin and flexible material where it may be found necessary to maintain the article in a stretched or distended condition. I wish also to be understood as not limiting my invention to the exact details of construction herein shown and described, as the 105 same may be altered in various particulars, and still be within the scope of the invention.

What I claim is:—

1. An article of the class described, comprising a bar, pins pivoted upon the face of the bar and having their points coacting with the face of the bar when in closed position and adapted to be opened outwardly from the face of the bar, and means for maintaining the pins in closed position. 110

2. An article of the class described, comprising a bar, pins pivoted upon the face of the bar and having their points coacting with the face of the bar when in closed position 115 and adapted to be opened outwardly from the face of the bar, and means for maintaining the pins in closed and opened positions.

3. An article of the class described, comprising a bar, pins pivoted upon the face of the bar and having their points coacting with the face of the bar when in closed position and extending longitudinally of the bar in opposite directions and adapted to be opened 125 outwardly from the face of the bar, and 130

means for maintaining the pins in closed and open positions.

4. An article of the class described, comprising a bar, bent pins pivoted upon the face of the bar and having their points coacting with the face of the bar when in closed position and extending longitudinally of the bar in opposite directions and adapted to be opened outwardly from the face of the bar, and means for maintaining the pins in closed and open positions.

5. An article of the class described, comprising a bar, front plates, spring plates secured in said front plates, means for securing said front plates and their attached spring plates to the ends of the bar, and pins pivotally arranged in said front plates and having heads interposed between said front and spring plates, whereby said pins are maintained in closed and open positions.

6. An article of the class described, comprising a bar, having recesses at its ends, front plates, spring plates arranged beneath in said front plates, pins pivotally mounted in said front plates and having heads interposed between said front and spring plates, whereby the pins are maintained in closed and open positions, and means for securing said plates and their attached pins in the recesses in said bar.

7. An article of the class described, comprising a bar having recesses at its ends, front plates having integral ears, spring plates arranged beneath said front plates and secured thereto by said ears, pins pivotally mounted in said front plates and having heads interposed between said front and spring plates, whereby the pins are main-

tained in closed and open positions, and lugs on said front plates for securing said plates and their attached pins in the recesses in said bar.

8. An article of the class described, comprising a bar having recesses at its ends, front plates having diametrically opposite ears and lugs, spring plates having diametrically opposite notches registering with the ears and lugs of said front plates and arranged beneath said front plates and secured thereto by the ears of said front plates engaging the complementary notches thereof, pins pivotally mounted in said front plates and having heads interposed between said front plates and spring plates, whereby the pins are maintained in closed and open positions, the said plates and their attached pins being secured in the recesses in said bar by passing the lugs of said front plates through the bar and securing them in place.

9. An article of the class described, comprising a bar, bent and shouldered pins pivoted upon the face of the bar and having their points coacting with the face of the bar when in closed position and extending longitudinally of the bar in opposite directions and adapted to be opened outwardly from the face of the bar, and means for maintaining the pins in closed and open positions.

In testimony whereof I have hereunto set my hand this fourth day of November A. D. 1908.
